UNITED STATES PATENT OFFICE.

PETER KRUSE, OF NEW YORK, N. Y., ASSIGNOR TO E. W. BLISS COMPANY, OF BROOKLYN, NEW YORK, A CORPORATION OF WEST VIRGINIA.

MACHINE FOR SEAMING HEADS ON CANS.

1,152,188.

Specification of Letters Patent. Patented Aug. 31, 1915.

Application filed May 22, 1914. Serial No. 840,184.

To all whom it may concern:

Be it known that I, PETER KRUSE, a citizen of the United States, residing in the borough of Brooklyn, county of Kings, city 5 and State of New York, have invented certain new and useful Improvements in Machines for Seaming Heads on Cans, of which the following is a specification.

This invention relates to machines for 10 seaming heads or ends on cans or can-bodies, and aims to provide improvements therein.

The machine of the present invention is of the type known as "two-spindle machines", and contains improvements whereby 15 the seaming operation may be under the ready and constant observation of the operator, and whereby any irregularities in the operation of the seaming mechanism 20 may be readily observed and quickly and readily rectified.

The invention further provides improvements in the general machine structure.

The invention further provides improvements in the seaming mechanism whereby 25 changes may be made for adapting the mechanism for operating on different sized cans with greater readiness than heretofore.

30 An embodiment of the invention is illustrated in the accompanying drawings, wherein—

Figure 1 is a front elevation; Fig. 1^a is a fragmentary side elevation of the top part 35 of the machine; Fig. 2 is a horizontal section on line 2—2 of Fig. 1; Fig. 3 is a horizontal section on line 3—3 of Fig. 1; Fig. 4 is a top-plan view with parts broken away to show one of the seaming mechanisms; 40 Fig. 5 is a diagrammatic view illustrating the action of the seaming rolls upon a can-head; Fig. 6 is a view in elevation (with parts in section and parts omitted) of the seaming mechanism; Figs. 7, 8 and 9 are 45 views of a similar seaming mechanism to that disclosed in Figs. 4, 5 and 6, Fig. 7 being a horizontal sectional view through the upper part of the seaming mechanism, Fig. 8 a diagrammatic view similar to Fig. 5, and Fig. 9 a vertical section of the mechanism with parts in elevation.

In said drawings, A designates a seaming

mechanism, and B a second seaming mechanism.

a and *b* are, respectively, the seaming 55 heads of the mechanisms A and B, carrying, respectively the seaming rolls *a'* and *b'*. The seaming heads *a* and *b*, respectively, are driven by the spindles C and D, which are rotated from a vertical drive-shaft E 60 through the intermediary of a gear *e* and pinions *c* and *d* respectively. The drive-shaft E may be driven in suitable manner by means of a pulley F mounted upon a horizontal shaft *f* and connected to the shaft 65 E through suitable bevel gears *f'*.

G designates a turntable which may be provided for receiving the cans. The turntable G is preferably driven from the main shaft E by sets of gears *g¹* *g²* on the shafts 70 *g³* *g⁴*.

H and I are feed tables for the cans or bodies, and J and K are feed disks. The feed disks J and K are intermittently actuated preferably through a Geneva wheel L 75 driven by a pin *l* mounted on the drive-shaft E, and gear wheels *l'* *l''* connected to the shafts *j* and *k* of the disks J and K. The feed disk J receives the cans from the turntable G and carries them past a suitable 80 selective can-head feeding mechanism M to a position beneath the first seaming mechanism A, and the feed disk K carries the cans with the heads partially seamed thereon to a position beneath the second seaming 85 mechanism B, where the seaming is completed, and from thence on to a suitable carrying-off device N. The feed disks J and K rotate in opposite directions, and the disk K rotates toward the front of the machine, in such manner that the cans with the partially seamed can-heads thereon, coming from the seaming mechanism A, are moved to the front of the machine, clear 90 of the seaming mechanism and in clear view 95 of the operator, where they may be readily observed or examined by the operator. The feed tables H and I are provided with guides *h* and *i* for the cans, and the guide *i* is preferably provided with removable or 100 pivotal portions *i¹* *i²* which may be readily swung open so as to provide for ready removal of the can for inspection or rejection. The feed disks J and K are adapted to

match beneath the first seaming mechanism in such manner that when the can is in position in the first seaming mechanism it is rounded or straightened up into its proper shape. The feed disks J and K therefore perform the two functions of feeding and shaping-up the cans.

When the cans are in seaming position beneath the seaming mechanisms A and B, 10 they are raised against the chucks a^2 and b^2 respectively of the seaming mechanisms by the plungers O and P respectively. The plungers O and P are actuated by a slide Q sliding in usual ways on the main frame, 15 which slide is raised and lowered by a cam q mounted upon the drive-shaft E which acts upon a roller q' upon the slide Q. The slide preferably acts upon the plungers O and P through resilient means such as 20 springs o and p.

The seaming mechanisms A and B (Figs. 4-9) comprise the seaming heads a and b , which are fixed upon the hollow rotary spindles C and D. The seaming rolls a' a' 25 and b' b' are carried by arms a^3 a^3 and b^3 b^3 respectively, fixed upon pins a^4 a^4 , b^4 b^4 , which are pivotally mounted in the seaming heads a and b respectively. The sealing rolls a' a' and b' b' are moved inwardly into 30 contact with the can-heads or ends by means of hoods or shells R and S carrying cams adapted to engage shoes a^5 a^5 and b^5 b^5 mounted on arms a^6 a^6 and b^6 b^6 fixed upon the pins a^4 a^4 and b^4 b^4 respectively. The 35 hoods or shells R and S are mounted upon rotary hollow shafts r and s respectively which are journaled in a slide T which is suitably guided upon the main frame of the machine, and is moved up and down by a 40 cam t mounted upon the drive-shaft E, the cam acting upon a roller t' carried upon the slide T. The shafts r and s are keyed to the spindles C and D and partake of the rotary movement thereof. Up and down 45 movements of the hoods R and S under the influence of the cam t brings the cams carried by the hoods into and out of contact with the shoes a^5 b^5 , and consequently effects the inward movement of the rollers 50 against the can-heads, and the release of the rollers, the rollers moving outwardly by centrifugal force.

The hoods or shells R and S are preferably formed as separate parts, and connected to flanges r^2 s^2 which may be provided upon the shafts r and s . The hoods R and S are preferably provided with a plurality of sets of cams r^3 r^3 , r^4 r^4 , r^5 r^5 , s^3 s^3 , s^4 s^4 , s^5 s^5 . The cams of the respective sets upon each hood are at different radial distances and are hence adapted to move the rollers inwardly to progressively greater extent, in such manner that the seaming rolls may be made to operate upon cans of different diameters by selecting an appropriate set of

cams. The several sets of cams on each of the hoods R and S may be brought into proper position for engaging the shoes connected with the several seaming rolls, by removing the bolts r^7 s^7 and shifting the hoods circumferentially to a proper position. For 70 positioning the hoods upon the shafts, the flanges r^2 and s^2 may be provided with a plurality of holes r^8 r^9 r^{10} , and the hood with a hole r^{11} through which a pin r^{12} is adapted 75 to be inserted into one of the holes r^8 , r^9 or r^{10} , as shown in Fig. 4. For convenience and expedition in placing the hoods on and taking them off the shafts r and s , the hoods are each constructed in two or more parts adapted to be separated and be brought together 80 around the shafts. The different parts may be connected by cleats r^{15} , as shown in Fig. 4.

The chucks a^2 and b^2 are carried by hollow sleeves a^7 a^7 extending through the hollow spindles C D and fixed in brackets a^8 b^8 at the top of the machine. Knock-outs U and V extending through the hollow sleeves a^7 b^7 may be provided. The knock-outs may be operated by a cam u which actuates a 90 roller v on the end of a rod v' connected to a rock-arm v^2 connected to the knock-outs U and V by means of links v^3 v^3 .

The feed mechanism M will be briefly described. In general construction it resembles the feed-mechanism disclosed in my 95 United States Patent No. 1,058,372, dated April 8, 1913.

m (Fig. 2) is a reciprocating slide carrying a pair of knives m' m' adapted to separate a single can-head from the bottom of a stack of can-heads in the hopper m^2 . The slide m is preferably operated by a lever m^7 connected by means of a pitman rod m^8 to a crank pin on a gear m^9 meshing with a gear 100 m^{10} fixed upon the drive-shaft E.

m^3 is a pusher adapted to push the separated can-heads from beneath the hopper. The feed of the can-heads is controlled by a reciprocating rod m^4 having a recess m^5 105 therein and connected to a bell-crank m^6 . The pusher m^3 normally rests within the recess m^5 in the rod m^4 . When a can passes the bell-crank m^6 , the bell-crank operates the rod m^4 , lifting the pusher out of the recess m^5 , and causing it, when carried forward by the slide m , to contact with a can-head and push the same from beneath the hopper.

When a can-body fails to operate upon the bell-crank m^6 the pusher m^3 will not be raised and will consequently fail to push out a can head when carried forward by the slide m . When a can-head is pushed from beneath the hopper, it is carried forward over its can by the feed disk J to the first seaming position, being supported by ledges h' on the guide H and ledges j' on the feed disk J. The feed disk J is also provided with ledges k' for supporting the can-heads, in conjunction with the ledges j' on the 115 120 125 130

feed disk J, over the cans in the first seaming position.

The turn-table G, the feed-table H, and the feed-table I are preferably mounted upon a common or unitary frame W (Fig. 3) which slides in guides w attached to the main frame of the machine. The frame W is adapted to be adjusted as a whole by the hand-wheel w'. By this means the adjustment of the machine to cans of different heights is facilitated.

The operation of the machine is as follows:—Cans or bodies x x are received upon the turn-table G and carried to the feed-disk J. The cans are thence carried to the first seaming mechanism A past the can-head feed mechanism M which operates to feed a head for each can fed to the machine. When the can reaches the first seaming position x¹, it is rounded by the feed-disks J and K and pressed upwardly by the plunger O into engagement with the superposed can-head and against the chuck a². The shell R is thereupon lowered by the cam t, bringing the cans carried by the slide R into contact with the shoes connected with the seaming rolls a' a', forcing the seaming rolls a' a' into contact with the can-head to clench and partially seam the same upon the can. The can with the partially seamed head thereon then descends to the level of the feed-table with the plunger, assisted by the knock-out U, and is thereupon fed by the disk K to a position at the front of the machine where the can can be readily and quickly observed, and removed if desired. The can thereupon passes the second seaming mechanism B. In this position (x²) the can is raised against the chuck b² by the plunger P and the seaming of the head upon the can is completed by the seaming mechanism B in a manner similar to the operation of the seaming mechanism A. The can thereupon descends with the plunger P, assisted by the knock-out V, to the level of the feed-table, and is fed from the machine, with the assistance of an ejector X, onto the carrying-off device N.

The invention may receive other embodiments than that illustrated and specifically described.

What is claimed is:—

1. In a machine for seaming heads on cans, a seaming mechanism adapted to partially seam a can head on a can body, and a second seaming mechanism adapted to complete the formation of the seam, an intermittently rotatable feed disk adapted to feed cans with the partially seamed can heads thereon from said first seaming mechanism to the second seaming mechanism across the front of the machine, and to stop the can in an intermediate position, and a guide for said cans around said feed disk, said guide having a removable portion co-

inciding with said intermediate stopping position, through which cans may be taken from the feed mechanism between said seaming mechanisms.

2. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism.

3. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, said feed disks having recesses therein adapted to partially embrace the cans, and said feed disks meeting at said first seaming mechanism, and being adapted to embrace the cans at each side, so as to round or true the cans at the first seaming mechanism.

4. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, said feed disks rotating in opposite directions, and said second feed disk rotating toward the front of the machine.

5. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, said feed disks rotating in opposite directions, and said second feed disk rotating toward the front of the machine, said feed disks having recesses therein adapted to partially embrace the cans, and said feed disks meeting at said first seaming mechanism, and being adapted to embrace the cans at each side, so as to round or true the cans at the first seaming mechanism.

6. In a machine for seaming heads on

cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, a feed table beneath each of said feed disks, and means for adjusting together the height of said feed tables.

7. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, a receiving turn-table, and a feed table beneath each of said feed disks, said turn-table and feed tables being mounted on a common frame.

8. In a machine for seaming heads on cans, a seaming mechanism adapted to partially seam a can head on a can body, and a second seaming mechanism adapted to complete the formation of the seam, an intermittently rotatable feed disk adapted to feed cans to said first seaming mechanism, and a second intermittently rotatable feed disk adapted to feed cans from said first seaming mechanism to said second seaming mechanism, a receiving turn-table, a feed table beneath each of said feed disks, said turn-table and feed tables being mounted on a common frame, and means for adjusting the height of said frame and the tables thereon.

9. In a machine for seaming heads on cans, a seaming mechanism, comprising a seaming head, seaming rollers carried thereby, and means for moving said rollers into seaming contact with a can head, said means comprising a vertically-reciprocating member, a divided seamer-actuating hood carried by said member and cam-parts carried by the divisions of said hood, whereby to change the cam parts the divided hood may be separated and its divisions removed and replaced.

10. In a machine for seaming heads on cans, a seaming mechanism comprising a seaming head, pivotally mounted seaming rollers carried thereby, and means for moving said rollers into seaming contact with a can head, said means comprising a vertically reciprocating sleeve, a divided seamer-

actuating hood its divisions separably attached to said sleeve and cam-parts carried by the divisions of said hood.

11. In a machine for seaming heads on cans, a seaming mechanism, comprising a seaming head, seaming rollers carried thereby, and means for moving said rollers into seaming contact with a can head, said means comprising a vertically reciprocating member, and an actuating hood thereon, said hood having cam parts adapted upon the vertical movement of the hood to communicate the operative movement to said rollers, and said hood being manually adjustable in circumferential direction to bring different active portions of said cam parts into operative engagement with the rollers, and said cam-parts having their different active portions of varying projection and thereby adapted to move said rollers inward to a greater or less extent according to the circumferential position of said hood.

12. In a machine for seaming heads on cans, a seaming mechanism, comprising a seaming head, seaming rollers carried thereby, and means for moving said rollers into seaming contact with a can head, said means comprising a vertically reciprocating member, and an actuating hood thereon, said hood having cam parts adapted to communicate movement to said rollers, and said hood being circumferentially adjustable, and said cam parts being adapted to move said rollers inward to a greater or less extent according to the circumferential position of said hood, said hood being split and being adapted to be put on and off around the seaming head axis.

13. In a machine for seaming heads on cans, a seaming mechanism comprising a seaming head, pivotally mounted seaming rollers carried thereby, and means for moving said rollers into seaming contact with a can head, said means comprising a vertically reciprocating member, and an actuating hood thereon, said hood having cam parts adapted upon the vertical movement of the hood to communicate the operative movement to said rollers, said hood being manually adjustable in circumferential direction and said cam parts having different active portions adapted to move said rollers inward to a greater or less extent according to the circumferential position of said hood.

In witness whereof, I have hereunto signed my name in the presence of two subscribing witnesses.

PETER KRUSE.
